NEEDLE THREADER

Julian Seth Kahn, New York, N. Y.

Application July 27, 1949, Serial No. 107,022

13 Claims. (Cl. 223—99)

1

This invention relates to an improved needle threader which is adapted to receive and thread sewing needles, embroidery needles, lacing needles, darning needles and the like, irrespective of their respective sizes and shapes, and irrespective of the relative positions of their eyes. The needle threader constituting the present invention is equally adapted to accommodate extremely fine thread, such as fine silk and nylon, and extremely heavy darning yarn, whether made of nylon, wool, silk, cotton, glass fiber, or the like, as well as thread of intermediate thickness, such as the cotton thread which is generally used by housewives for mending purposes. The needle threader constituting the present invention is of relatively fool-proof design in that it functions properly and efficaciously with respect to all commercial needles of the types above mentioned. It is indeed a most versatile instrument which performs its assigned work efficiently.

In needle threaders of the prior art of the general type referred to herein, a threading arm was first passed through the eye of a needle by manual pressure which was applied from the rear against the pressure of a spring, and then the thread was draped over the arm and the manual pressure released to permit the spring to withdraw the arm carrying the thread through the eye.

There were several hazards to this:

First, the manual pressure from the rear tended to force the arm (whether it registered with the eye or not) so that frequently the arm ricocheted off the side of the needle without going through the eye. Thus, the arm was frequently bent, and this destroyed the value of the threader for further use.

Secondly, by pushing from the rear the manual pressure is substantially uncontrolled and the arm, having some vertical play, may not adjust itself vertically to pass into the eye of the needle and thus may strike the metal of the needle and bend or break.

Thirdly, the finger must retain pressure on plunger against the tension of the spring. If threading cannot be done very quickly, the finger may relax its pressure and thus the thread will miss the threading arm since the spring will retract the arm slightly.

Fourthly, it was not possible to thread an assortment of needles in prior art devices except to very limited extent. Nor could very thick thread or many plies of any thread be used with such old devices.

With the threader of the present invention, a bunch of thread which is much thicker than

2

the width of the eye of the needle, may be passed through said eye. With a threader of the present invention, 20 or more strands of No. 60 thread may be passed through the eye of a number 1 needle. The reason for this is that the thread is being pushed through the eye of the needle with the hooked threading arm by manual pressure as distinguished from spring pressure. Two things happen in response to the pressure: the thread or yarn is squeezed together in order to get through the eye, and when fully squeezed, if the yarn or thread will not yield any further, the walls of the eye of the needle actually yield or bulge to permit the arm to pull the thread through.

Other threaders are made to take a particular size of thread and needle while the threader herein described will take large variety of sizes of thread and of needles.

20 It is accordingly the principal object of this invention to provide a needle threader of the character described which is self-adjustable to accommodate all of the different types of needle in all of their respective sizes and shapes. 25 No conscious effort on the part of the operator is required to set or adjust the present needle threader to enable it to accommodate the needles. Instead, its needle threading member automatically cams itself upwardly to properly align the threading arm relative to the eye of very large needles. Where the eye is so extremely positioned as in the case of a very small needle, that the threading arm cannot align itself therewith, it automatically cams the needle to bring its eye into alignment with the threading arm. 30 The reciprocating member carrying the threading arm functions two ways, therefore, to provide accurate alignment between the threading arm and the eye of the needle: it either cams the arm into such alignment or it cams the needle into alignment with the arm.

Another principal object of the present invention is the provision of a needle threader of the character described wherein manual pressure is used to force the thread through the eye of the needle. Gentle spring pressure moves the threading arm through the eye in the first instance and the operator's finger, generally the thumb, is used to force the threading arm and thread back through the eye in the threading operation, the point of the threading arm being directed toward the finger-applying end of the plunger. This feature is extremely important since more pressure is generally required to force the threading arm through the eye when a thread is mounted thereon than when the threading arm is unen-

cumbered. In virtually all of the needle threaders currently on the market, finger pressure is applied to the reciprocating member in the first instance to insert the threading arm through the eye of the needle and spring pressure is depended upon to force said arm in the opposite direction and out of the eye when a thread is mounted thereon. When the thread happens to be relatively heavy or the eye relatively small, spring pressure may be found to be insufficient to force 10 the arm and the thread through the eye at the same time.

Another object of this invention is the provision of a needle threader of the character described which is operable by simply inserting the 15 needle into a suitable receptacle and then actuating the reciprocating threading member. In many threading devices of the prior art, it is virtually as difficult to find the needle receptacle as it is to find the needle eye and it is at times rather questionable whether it is more difficult to thread the needle with the unaided eye or to insert the needle into proper operative position in the needle threader. In the present invention, on the other hand, there is no problem whatsoever in accurately locating the eye of the needle 20 relative to the threading arm in the needle threader. There is a relatively large hole or well which may be many times the diameter of the needle. Its open end flares outwardly to even greater dimensions so that it is no trouble at all to find the well for the purpose of inserting the needle therein. In many of the needle 25 threaders of the prior art, this well is used for needle alignment purposes, and it must, therefore, necessarily be of relatively small diameter. In the present device, however, it is not the hole or well primarily, but rather its closed conical end or seat which properly vertically positions the needle, and hence the hole may be so dimensioned as to render it easy and convenient to 30 insert a needle therein.

In order to provide a needle threader which will handle all commercial hand-sewing needles from the finest to the largest, and incidentally handle fine filament threads in single or multiples to the large, heavy darning wools, it is necessary to facilitate the withdrawal of the thread by having a generally vertical slot communicating the needle hole of the threader with the outside 35 of the casing. This slot must be large enough to provide for the exit of many thicknesses of thread or of considerable thickness of a single thread or yarn. However, if a small needle were put into the well of the needle holder, it would tend to fall over and out through the slot before the needle could be threaded. Hence, it is an object of the invention to provide in a needle 40 threader which has a relatively large hole or pocket or well for the reception of various sized needles, a slot of zig-zag formation, or a slot with interspersed barriers which would retain a needle even of the very smallest diameter, in upright position, while still permitting the free passage of the thread or yarn upwardly through the slot.

Still another object of this invention is the provision of a needle threader of the character described wherein the hooked threading arm is integral with the finger piece or plunger which actuates it and with the spring which returns it to its normal or inoperative position.

All the internal working parts, that is, the reciprocating member, the threading arm, and the spring are stamped out of the same piece of sheet material, preferably stainless spring steel, of 55

hardness test of around 400 Vickers. A bending operation is required to form the spring. This constructional feature makes for great economy in production and it also makes for highly serviceable, lifetime use of the needle threader incorporating said features. It also makes for greater accuracy and uniformity in construction since no relative assembly of these parts is necessary, which also makes for economy.

A still further object of this invention is the provision of a needle threader of the character described, which has two needle threading arms, one of which functions automatically in accordance with the principles of the present invention and the other of which is operable in connection with needles of non-commercial or special size and shape. Both needle threading members may be integral with the same reciprocating member or plunger and they may be both integral with the same spring so that both threading arms, the finger piece and the spring may be stamped out of the same piece of sheet material.

Another object of this invention is the provision of a needle threader of the character described whose housing has a shank so fashioned that the threader may be mounted in a hole formed in a table or in a loop formed by a strap, or in any other suitable place. More specifically, the housing is provided with a tapered shank portion or appendage which is insertable into any suitable opening so that the device may very conveniently be put aside when it is not in use, and it may equally conveniently be picked up whenever it is desired to use it. For example, the tapered shank may be inserted into the axial opening of a thread spool. The tapered shape of the shank will enable it to fit rather tightly in the hole of the spool so that the spool may be used as a handle for the needle threader to render the threader more convenient for use and to have the thread readily available. The shank is specifically shaped to wedge into the center hole of a thread spool.

A still further object is to provide a device to be used for threading all commercial hand-sewing needles, from the very smallest No. 10 to the very largest No. 1, and to that end, the construction is such that for small needles, the bill of the threading arm as it seeks to enter the eye, will act as a cam to raise the small needle enough to permit entry of the arm through the eye, and with the large needle, the bill of the threading arm will contact the bottom wall of the eye and the reciprocating member itself with its threading arm will rise to enter the eye. That is to say, with the smallest of needles, the needles are raised, while with the larger needles the reciprocating member and the threading arm will rise. The arm, reciprocating member and its spring are so constructed and arranged that the spring pressure maintains the forward end of the reciprocating member yieldingly against the bottom of its slot, thus permitting the threading member to rise and ride into the eye of a large needle, while being adapted to cause the small needle to rise up for the threading arm to enter its eye.

An additional object of this invention is the provision of a combination needle threading device and holder therefor. The needle threading device herein described and claimed may very conveniently be mounted upon a conventional sewing thimble, and it may very readily be attached to a suction cup which will adapt it for mounting upon any suitable plane surface.

Still another object of this invention is the pro-

vision of a needle threader whose housing is so shaped that it may be held in one hand when in use, the other hand being free to apply the thread thereto with great ease. The housing is provided with a V-shaped channel or throat which receives the thread and precisely directs it to the threading arm so that said arm may automatically engage the thread for drawing through the needle's eye.

The aforementioned objects are among the more important objects of the present invention, and it will be understood that the invention has other useful objects which will become apparent from a reading of the specification.

Preferred embodiments of the present invention are shown by way of illustration in the accompanying drawing, in which:

Fig. 1 is a perspective view of a needle threader comprising an embodiment of this invention, and showing how it is held in the hand preparatory to threading a needle.

Fig. 2 is an enlarged perspective view of another embodiment of the needle threader.

Fig. 2a is a cross-sectional view taken on line 2a—2a of Fig. 2, and showing a thread draped over the threading arm.

Fig. 2b shows fragmentary perspective sectional views of alternative forms of the finger piece or plunger.

Fig. 3 is an enlarged view of the needle-holding portion of the casing of the device, showing the serpentine channel through which the thread is drawn after it has been inserted through the eye of the needle.

Fig. 3a is a view similar to Fig. 3, but showing a modification thereof.

Fig. 4 is an inside view of one of the halves of the casing, showing how it is cut out to accommodate the several moving parts of the device.

Fig. 5 is a similar view of the other half of the casing.

Fig. 6 is a fragmentary view similar to that of Fig. 4, showing how the needle threading member with its finger piece and spring portion connected thereto are mounted in said casing.

Fig. 6a is a fragmentary elevation of the inside face of one of the halves of the casing with the reciprocating threading member in retracted position therein.

Fig. 6b is a sectional view taken on line 6b—6b of Fig. 6a.

Fig. 7 is an enlarged fragmentary vertical elevation of the inside face of one of the halves in the zone of the needle holding portion of the casing, and showing the dart-shaped needle threading arm in position to engage a needle and enter its eye.

Fig. 8 is a perspective view of the reciprocating member together with its integrally attached finger piece threading arm and spring.

Fig. 9 is a similar view of a modified form thereof, showing an additional threading arm connected thereto, and integral therewith.

Fig. 9a is a longitudinal sectional view through the needle threader, utilizing the modification shown in Fig. 9.

Fig. 10 is an enlarged fragmentary vertical elevation of the inside face of one-half of the needle-holding portion of the casing, and showing a modification of the conical seat in the needle well.

Fig. 10a is a sectional view taken on line 10a—10a of Fig. 10.

Fig. 11 is a fragmentary view showing how an additional needle threading member is used.

Fig. 12 is a perspective view of a needle threader

made in accordance with the present invention, showing said needle threader mounted on a thimble.

Fig. 13 is another perspective view of a needle threader, showing a needle-holding casing with a hole formed therein to receive the tapered shank of the needle threader.

Fig. 14 is another perspective view showing the tapered shank of the needle threader in position to enter a hole formed in another type of needle kit or container.

Fig. 15 is a perspective view of a spool of thread showing how the tapered shank of the needle threader may be mounted in the hole formed in said spool.

Fig. 16 is a fragmentary perspective view of a table showing a hole formed in one of the side boards thereof and showing a looped strap attached to the table portion thereof, said hole and said looped strap being adapted to receive the tapered shank of the needle threader.

Fig. 17 is a perspective view of a suction cup showing how a hole may be formed in the side and in the end thereof to selectively receive the tapered shank of the needle threader.

Fig. 18 is a longitudinal elevational view of the inside face of one of the halves of a needle threader with a needle disposed therein, and shown in section, and showing the reciprocating member therein and a thread being drawn through the eye of the needle.

Referring now to the first form of this invention, it is clearly shown in Figs. 4 and 5 that the body or casing of the needle threader, identified in Fig. 2 by means of the reference character 20, comprises a pair of complementary parts 20a and 20b, respectively. These parts of the body may be made of any suitable material such as plastics, and they may, if desired, be molded or cast to the respective shapes which the drawing shows them to have. More specifically, body member 20a has a vertically extending main body portion 25a, a horizontally extending tapered shank portion 26a on one side of the main body portion, and a vertically extending finger 27a on the other side of the main body portion, said finger bearing at an acute angle with respect to said main body portion. It will be seen in Fig. 5 that complementary body portion 20b is provided with a corresponding main body portion 25b, a corresponding tapered shank portion 26b, as well as a corresponding finger portion 27b.

Body portion 20a is provided with pins or dowels 28a, 29a, 30a, and 31a, respectively, and body portion 20b is provided with registering holes 28b, 29b, 30b and 31b, respectively, which tightly accommodate said pins. Body portion 20b is provided with pins or dowels 32b, 33b and 34b, respectively, and body portion 20a is provided with corresponding holes 32a, 33a and 34a, respectively, which are adapted to register with, and accommodate, pins 32b, 33b, and 34b, respectively. The body or casing of the needle threader under discussion consists simply of the two body portions 20a and 20b above described, pinned or dowled together by the pin and hole means above mentioned. Pins 28a and 29a perform the further function of providing bearing surfaces for the slidably movable part of the device herein-after described. Obviously, the two body portions may be joined by means other than doweling. For instance, a raised flange may be provided on one body portion to fit a rabbet in the other body portion and cement may be used to secure the parts together.

It will hereinafter more fully appear that the main body portion of the casing accommodates the needle and the threading mechanism and that the tapered shank portion accommodates the additional or auxiliary needle threading member.

A vertically extending groove 40a is formed in main body portion 25a and a corresponding groove 40b is formed in main body portion 25b. These grooves are closed at their respective lower or inner ends 41a and 41b respectively, and they flare outwardly at their upper or outer ends 42a and 42b respectively. When the two body portions are joined, inner face to inner face, grooves 40a and 40b complement each other to form a substantially cylindrical hole or well which flares outwardly at the top open end and which is closed at its lower, inner end. This is the needle receiving well which is identified in Fig. 2 as well as in other figures by means of the reference character 40.

The outwardly flared or funnel-shaped open end of the hole is well adapted to receive the needle and to guide it into the main, cylindrical portion of the hole. The closed bottom end of the hole is tapered to conical shape, the conical wall being separated from the axial center of the hole by an angle of about 55°. Diametrically opposite portions of the conical wall are, therefore, about 110° apart to form a conical seat 43. (See Fig. 7.) The conical seat is important because since the needle well is large enough to receive the largest commercial hand-sewing needles, it is of considerably greater diameter than most of the needles for which it will be used. The conical seat will cause all needles to gravitate toward the center of the seat and thus the needle and the needle well will be coaxial. Hence, the eye of the needle will be vertically aligned with the threading arm. Now when the bill of the hooked arm is projected by the spring 82 it might have a tendency to push the very small and hence light needles up the slope of the conical seat. To overcome this tendency there is provided at the base of the seat, a narrow channel 41c approximately .008 of an inch wide and approximately .012" long. In this form the conical seat 43 will readily accommodate all but the two largest sizes of commercial hand-sewing needles, that is, Nos. 1 and 2. However, in the modification shown in Fig. 10, no such limitation exists. The conical seat 44 in this case, is designed to include near its apex the same angle as shown and described with respect to Fig. 7, but toward its base its angle becomes more obtuse relative to its axis, and for smoothness it is curved so one portion blends into the other to provide a seat into which all needles will gravitate toward the center of the needle well. This form (Fig. 10), as in that shown in Fig. 7, has a narrow depression or channel 41d, into which the butt ends of the very small needles will seat when they are rotated to align their eyes with the point of the threading arm. In Figs. 7 and 10, it will be seen that the eyes of small needles 62S will overlap the eyes of the large needles 62L when they are resting on the conical seat.

It will be seen in Figs. 4 and 5 that angular cut-outs 50a, 51a and 52a, and 50b, 51b and 52b, respectively, are formed in main body portions 25a and 25b along one side of grooves 40a and 40b, respectively. These several cut-outs open into said grooves 40a and 40b, respectively, so that communication may be had with said grooves through said cutouts. When the two complementary parts of the body or casing of

the needle threader are brought together in the manner above described, cut-outs 50a, 51a and 52a cooperate with cut-outs 50b, 51b and 52b in staggered relation to form, in effect, a serpentine channel similar, though differently shaped from channel 50 (Fig. 3), which communicates with well 40. As Fig. 3 clearly shows, channel 50 is the passageway through which thread 60 travels after it has been inserted through the eye 61 of needle 62 and the needle is being withdrawn from the needle threader. It is not essential that the shape of channel 50 be serpentine but it is important that a straight channel which is parallel to well 40 be avoided since a small needle might slip through such channel.

In the modification shown in Fig. 3a, lugs 56 are provided to extend alternately from each side of the casing past the medial line thereof. This arrangement forms the serpentine channel 50 above mentioned. It will be noted that in this modification, the lugs 56 have beveled or angulated upper faces which serve to cause the butt end of the needles to glide off these lugs, should the needle, in passing down into the needle well tip over and encounter the top of any of these lugs.

The diameter of needle well 40 should exceed the diameter of the largest needle which the needle threader is designed to thread. Its depth should, however, be exceeded by the length of the shortest needle, said thresher is intended to accommodate, so at least part of the needle will protrude sufficiently to permit grasping by the hand. The width of serpentine channel 50 should exceed the diameter of the heaviest or thickest thread or multiple threads which it is possible to pack through the eye of a needle and which may be used in connection with the needles said thresher is adapted to accommodate.

It will be noted in Fig. 4 that cut-outs 53a and 54a are provided in body portion 25a and that corresponding cut-outs 53b and 54b are provided in body portion 25b. Cut-outs 53a and 54a are horizontally aligned with each other on opposite sides of groove 40a and it will be noted in Fig. 5 that cut-outs 53b and 54b are horizontally aligned with each other on opposite sides of groove 40b. These several cut-outs communicate with grooves 40a and 40b respectively, as well as with each other when the two body portions are secured together. They are formed a predetermined distance above the conical closed end of hole 40, said distance being determined by the distance between the eyes of the several needles which may be accommodated by this needle threader and their respective butt ends. These cut-outs are so positioned and their dimensions are such that they register with the eye of every needle which the needle thresher is adapted to accommodate when the butt end of said needle rests upon the conical seat 43 or 44, as shown in Figs. 7 and 10, respectively. It should be stated here, and it will more clearly hereafter appear, that these cut-outs last mentioned constitute the passageway through which the thread may pass during the course of the needle-threading operation. Were it not for such cut-outs, there would be insufficient clearance at the sides of the needle-threading arm proper. Note that this thread passage is tapered from the throat toward the rear thereof, the wider portion being at the entrance to the passage so when the bight of one or more threads are pushed by the hook, the tapered passage

will serve as a lead-in to the needle eye. (Fig. 6b). It should also be observed that the rear of this thread passage is so dimensioned that after the hook has drawn the thread or threads through the needle eye the thread bight will be held in place so long as the hook slide is held against spring tension and while the needle is being withdrawn from the needle well. Thus the needle is sliding along a secured thread until the user is satisfied as to the extent or length of thread that has passed through the needle, at which time the plunger or slide may be released to permit the spring to project the barb to release the thread.

A relatively wide, horizontally extending recess 70a is formed in main body portion 25a and partly in finger portion 27a to accommodate reciprocating member 81, and a corresponding recess 70b is formed in main body portion 25b and finger portion 27b. A somewhat deeper and substantially triangular recess or cavity 71a is formed in main body portion 25a and a corresponding but slightly larger recess or cavity 71b is formed in main body portion 25b. When the two body portions of the device are secured together in the manner aforementioned, recesses 70a and 70b register with each other and recesses 71a and 71b register with each other and all of said recesses have communication with each other and cooperate to accommodate the moving parts of the needle threader.

The movable parts of the needle threader are three in number: the needle-threading arm 80, the finger piece or plunger 81 and the spring 82. (See Fig. 8.) Needle-threading arm 80 comprises a horizontally extending arm which has a pointed bill at its forward end and a hook 80c immediately behind its pointed forward end. For purposes of convenience both in the specification and the claims member 80 will hereinafter be designated and identified as the threading arm. The thickness of this threading arm should be such as to enable it to pass through the smallest eye of the smallest needle which the needle threading device is designed to accommodate. There should, moreover, be sufficient clearance on both sides of the threading arm to enable the thread to pass through the eye of the needle simultaneously with said threading arm.

Plunger 81 consists of a finger piece or thumb piece 81a and a horizontally extending slide bar 81b. A vertically extending portion 80b projects upwardly from horizontal bar 81b and supports the horizontally extending threading arm 80. A predetermined space is thereby provided between the pointed forward bill end of said threading arm and thumb piece 81a and a predetermined space is thereby also provided between said threading arm and horizontal bar 81b.

Bent substantially at right angles to horizontal bar 81b is a spring root plate 82a which continues upwardly as spring 82. It will be noted that before the bending operation of spring 82 and its root 82a from the plate 81b, the metal is sheared as at 80c from the top edge to very near the bottom thereof. Spring 82 projects upwardly at an angle of approximately 15° off the vertical. It may be bent at its upper end to form a curved portion 82b; however, this bend may not be necessary. It will be seen in the drawing that thumb piece 81a, horizontal bar 81b, vertical portion 80b, threading arm 80, plate 82a and spring 82 are all integral with each other. All of said parts combined constitute a

single stamping. As has already been noted, the sheet material from which the stamping is made should preferably be stainless spring steel.

The stamping last above described and best shown in Fig. 8 is mounted in the casing in the manner shown in Fig. 6. Spring portion 82 is disposed in the spring chamber, formed by combined recesses 70a and 70b. Hooked end threading arm 80, vertical portion 80b, horizontal bar 81b and a small part of thumb piece 81a are normally mounted in the chamber formed by combined recesses 70a and 70b. The major portion of thumb piece 81a projects outwardly from the casing as Fig. 6 and Fig. 2 clearly show.

At the upper end of recess 71a, and projecting into the upper end of recess 71b, is a shoulder 85 against which curved portion 82b of spring 82 bears. Shoulder 85 may have a relatively flat or a relatively curved bearing surface and said surface should preferably be disposed at an angle of approximately 45° with respect to the vertical. The shape of spring 82 is such that when its curved end portion 82b bears against shoulder 85, it ends to urge the rest of the stamping, that is the hook-shaped threading arm 80, thumb piece 81a and portions 80b, 81b and 82a leftwardly and downwardly, as seen in Fig. 6. Finger pressure is required to push these several parts to the dotted line position shown in Fig. 6 and this movement, rightwardly of the solid line position shown in Fig. 6, takes place against the action of spring member 82.

The shape and angle of inclination of shoulder 85 are important to the smooth functioning of 35 the device since radically changed shape and angle of inclination may produce a binding effect with respect to spring 82. Furthermore, the slide which includes the thumb piece 81a, threading arm 80 and portions 80b, 81b and 82a, engages

40 in other than strictly horizontal, reciprocatory movement. It also moves both vertically and pivotally as the arrows in Fig. 6 clearly show, although, to be sure, such movement is on a relatively small scale by comparison with the extent of the horizontal movement of said slide. It will hereinafter more clearly appear that the slide is adapted to move both vertically and pivotally to enable its threading bill to enter the eyes of some needles. The shape and angle 45 of inclination of shoulder 85 are conducive to such vertical and pivotal movement. It may also be found desirable, to avoid binding in the action of spring 82, to form recesses 71a and 71b in unequal sizes. This would have the effect of preventing the spring from catching upon the edges of casing members 20a and 20b along the periphery of recesses 71a and 71b, and more especially in the area of contact with said spring.

An island or boss 90a is formed in recess 70a 50 immediately below needle groove 40a, and a corresponding island or boss 90b is formed in recess 70b immediately below needle groove 40b. These two islands occupy the space between threading arm 80 and horizontal slide bar 81b, when the 55 slide is spring projected. Said threading arm occupies the space between said islands and the top wall of the chamber formed by recesses 70a and 70b. There is, however, sufficient clearance to enable the threading arm 80 to engage in slight vertical and pivotal movement in the manner and for the purposes above set forth.

Islands 90a and 90b perform two important 60 functions: they assist in guiding the slide in its horizontal movements and they also provide the 65 needle seat which has above been identified by 70 75

means of the reference characters 41a and 41b. Elements 41a and 41b have above been described as constituting the closed lower ends of grooves 40a and 40b respectively. When the two casing portions 29a and 29b are joined in the manner 5 above described, closed ends 41a and 41b of grooves 40a and 40b combine to form needle seat. This seat is conical in shape as has above been noted, to receive the butt end of the needle.

It will be observed that the slide is so constructed that its bill 80a is directed to point toward the finger piece 81a and also that the slide bar 81b slides directly under the needle seat.

A typical threading operation may now be described. The first step is to push thumb piece 81a inwardly with one hand, as viewed in Figs. 2 and 6, against the tension of the spring. This causes the threading arm to move inwardly past needle well 40 and tends to align the needle eye with the threading arm. Needle 62 may be 20 dropped downwardly into said needle well until its butt end rests upon seat 43 or 44. It will be found that by reason of the conical shape of seat 43—44 and the fact that it is composed of two separate portions 41a and 41b, that the needle will tend to automatically position itself on said seat in such manner that its eye 62a is in alignment with threading arm 80. Thumb piece 81a may now be released and spring 82 will move said thumb piece as well as barb-shaped member 89 and portions 89b and 81b outwardly until said barb enters needle eye 62a. If perchance the needle eye is out of alignment with the barb-shaped member, the thumb piece should be actuated or manipulated once or twice to cause the barb-shaped member to engage the needle and thereby to cause the needle to turn sufficiently to align its eye with the hooked end. Another way of accomplishing the same result is to leave the threading arm in its normal position athwart needle well 40. The needle is then dropped into the well and the thumb piece is actuated to move the threading arm inwardly against the action of spring 82. Sliding contact is thereby provided between the barb-shaped arm and the needle and this has the effect of causing the needle to turn into accurate alignment with the barb-shaped arm, especially at the moment that said barb-shaped arm moves a sufficient distance to the right to clear the needle. When the thumb piece is released, spring pressure causes the barb-shaped arm to move outwardly into and through the eye of the needle.

Thread 60 may now be draped over the barb-shaped arm in the manner shown in Figs. 1 and 2a. It will be understood, as Figs. 2 and 6 clearly show, that a part of said barb-shaped arm is exposed in the V-shaped space or thread throat 35, which separates main body portions 25a and 25b from fingers 27a and 27b. The ends of the thread may be permitted to hang downwardly as shown in Fig. 1, or they may be held by the fingers of the free hand and pulled downwardly so that the bight of the thread is relatively taut about the barb-shaped arm (Fig. 2a). The thumb piece is once again pushed inwardly to its limit, that is, toward the right as viewed in Figs. 1, 2 and 6, and in so moving, the hook 80a engages the thread and pushes it through the eye of the needle. It is during this latter process that the thread passes through thread-receiving slot formed by tapered recesses 53a and 54a and tapered recesses 53b and 54b. The needle is now threaded, and it should be removed from well 40.

As it is brought upwardly through said well, while maintaining pressure on the plunger, it slides along the thread 60 and said thread travels through the sinuous channel 50 which has been above described. (See Fig. 3.) The needle is double threaded, and it may be used in that condition or one of the ends of the thread may be pulled outwardly through its eye to leave only a single thread therein. When the needle is withdrawn for the desired length of thread, the plunger is released to permit the hook to release the bight of the thread.

The needle seat should be so arranged that the eyes of the smallest commercial hand-sewing needle, say a No. 10, and of the eye of the largest commercial hand-sewing needle, say a No. 1, either Shaprs or Crewels, would overlap about .005 of an inch. When the smaller of these two needles is placed in the needle hole, the threading arm will cam the needle upwardly in order to gain access to the needle eye and when the larger of these two needles is placed in the needle well, the threading arm will cam itself upwardly to enter the eye of said needle. A combined vertical and pivotal movement of the threading arm may be required in this latter operation to bring itself into alignment with the eye of the larger needle.

It has been stated that the threading arm, the 30 spring and plunger are all stamped from a common sheet of stainless spring steel. This material should be approximately .004 to .005 of an inch in thickness, and it should be hardened to such an extent as will enable it to be bent at 35 right angle on about a .015" radius without cracking or breaking. It has been found that a hardness of about 400 Vickers has been satisfactory.

Tapered shank 26a is provided with a recess 100 which extends longitudinally and horizontally thereof. Pins 30a and 31a extend in said recess. It will be seen in Fig. 2 that this recess is adapted to receive an auxiliary dart-shaped threading member 101 which has a cut-out 102 formed therein to accommodate said pins 30a and 31a. These pins assist in guiding said auxiliary member when said member is pulled outwardly from its said recess or pushed inwardly thereinto and pin 30a prevents said auxiliary member from leaving its said recess. This auxiliary member may be used to thread any needle larger than those that can be accommodated by the main threading member. The manner in which this auxiliary threading member may be used is best shown in Fig. 11 where a similar though modified form of threading member appears. The dart is inserted through the eye of the needle, the thread is then looped about the dart and the dart is then pulled outwardly from the eye of the needle, thereby pulling the thread with it and thus threading the needle.

Fig. 9 shows how an auxiliary threading member 110, similar to auxiliary threading members 101 and 105, may be made integral with main threading member 111 which is similar to the barb-shaped threading member 80 above described. This needle threading device has a spring 112 which is similar to spring 82 and a plunger 113 which is similar to plunger 81. Spring 112 extends from plate 114 which is similar to plate 82a and a horizontal bar 115 extends from said plate 114 and continues outwardly to form auxiliary threading member 110. The two threading arms 110 and 111, as well as bar 115, plate 114, plunger 113 and spring 112 are all integrally stamped and formed from a single sheet

of spring material. When this double ended threading device is incorporated into a casing similar to casing 20 above described, recess 100 is extended to communicate with recess 71a. Both threading members 110 and 111 may, therefore, be actuated by the same plunger 113 reciprocating with respect to the same casing.

In the modification shown in Fig. 11, the reciprocating member slidably mounted in casing 106 includes thumb piece 108, principal threading arm 109 and auxiliary threading arm 105. A compression spring 107 urges auxiliary threading arm 105 to the left to its retracted position. Thumb piece 108 may be pressed rightwardly, as viewed in the drawing, to move auxiliary threading member 105 to its projected position shown in Fig. 11 against the action of spring 107.

Figs. 1 and 12 to 17, inclusive, show how the tapered shank 26 which comprises portions 26a and 26b may be used to assist in holding the threading device in the hand during use. It will be seen in Fig. 1 that said tapered shank may be held between the forefinger 120 and the third finger 121 to render the thumb piece 81 accessible to thumb 122 for actuation thereof. The other hand is thereby left free to put the needle into the needle well and to drape the thread over the barb-shaped needle threading arm. Said other hand is also free to remove the needle from said threading device after it has been threaded.

The casing of the threading device under discussion may be provided with a hole 125 through which a string may be looped so that said needle threading device may be hung from about the neck of the person using the same, or it may be hung from a nail or hook on a conveniently located wall or table, such as table 121. If desired, a hole 128 may be formed in said table to accommodate said tapered shank 26; or a looped strap 129 may be attached to the table for the same purpose. A ring-shaped member 130 may be attached to a conventional thimble 131 as shown in Fig. 12. The tapered shank 26 may then be inserted into the ring 130 so that the needle threading device may be held in operative position by simply placing the thimble on one of the fingers in conventional manner. In Fig. 15, tapered shank 26 is shown inserted into the hole of an ordinary spool of thread 133. In Fig. 13, a needle containing kit 135 is shown which is adapted to receive a thimble 136 at one end thereof and which has a hole 137 formed at the opposite end thereof to receive the tapered shank 26 of the needle threading device under discussion. In Fig. 14, a second type of needle containing kit 138 is shown with a hole 139 formed therein to receive said tapered shank 26. In Fig. 17, a suction cup 140 is shown having a projection 141 formed thereon with one or more holes 142 formed therein. These holes may extend both axially and transversely of said projecting portion 141 to accommodate tapered shank 26. The suction cup may be mounted on any suitable surface.

It will be appreciated from the foregoing that the present device has been described in its preferred forms only and it may assume other forms as well as modifications of the preferred forms within the broad scope of the invention.

Having thus described my invention, what I claim as new and desire to secure by Letters Patent, is:

1. A needle threader adapted to accommodate all commercial size hand-sewing needles comprising a two-part housing, a vertical needle-well in

said housing, a transverse guideway in said housing, a reciprocating member closely slidably housed within said transverse guideway and comprising a sheet metal stamping having a hooked threading arm as an integral part of said member extending from the rear end of said member forwardly, said hooked arm terminating in a pointed bill, said threading arm being spaced apart from a lower portion of said member, a leaf spring bent from and extending as an integral continuation of the reciprocating member upwardly and rearwardly from said member with an actuating portion of said member extending forwardly, outwardly beyond said body portion to be operatively engaged by a person's finger, said needle-well being adapted to receive a needle for longitudinal and axial movements only until its eye lies in the path of said hooked threading arm, a notched throat in said body to receive a thread to be engaged by said hook of the threading arm for drawing it through the eye of a needle disposed in said well, said spring being adapted to be flexed when the reciprocating member is being moved rearwardly and adapted to straighten out to pass the hook of the threading arm through the eye of said needle as the reciprocating member moves forwardly under the influence of the spring, and cooperating members on the reciprocating member and on the housing for clamping the loop of a thread stationary when said member reaches its inward limit of movement immediately after the hooked threading arm is withdrawn from the needle after threading the latter.

2. A needle threader as claimed in claim 1 and having a conical seat in the housing at the bottom of the well to rotatably support the butt end of the needle with the eye of the needle in alignment with the hooked threading arm, the angle of the conical seat being obtuse and of such degree that when any commercial size hand-sewing needle rests on said seat the eye of the needle will be in position for the pointed bill and the needle to cooperate to lead the bill through the eye of the needle, said reciprocating member having free limited vertical movement.

3. A needle threader as set forth in claim 2, wherein a cavity is provided in the housing for accommodating the leaf spring, said cavity being much wider than the width of the spring to allow freedom of movement of said spring to find its own seat.

4. A device as set forth in claim 3, further characterized by the fact that the cavity in the casing is arranged so that the parting line between the two halves of the housing is off center so that the reciprocating member will ride on solid material and never on the parting line or crack between the parts.

5. A needle threader adapted to accommodate all commercial size hand-sewing needles and comprising a block having a needle-well therein opening to the top of the block, a cavity within said block, a guiding channel in said block substantially normal to said needle well and communicating with said cavity and intersecting said needle-well, an island disposed in said channel in spaced-apart relation to the top guiding surface of said guiding channel, a conical seat in said island, said seat being in axial alignment with said needle-well, a vertically disposed slot through said block communicating with said needle-well, said slot being vertically sinuous to bar a needle in the needle-well from falling out through said slot, a reciprocating member

of stainless spring steel having a finger piece on the front end thereof and having a portion extending rearwardly and then upwardly and then re-entrantly forwardly, said latter portion constituting a threading arm, a hook on the upper edge of said threading arm near its free end, said hooked portion terminating in a pointed bill, the rear of said reciprocating member having an extending portion bent normal to the plane of said member and extending upwardly and rearwardly to serve as a leaf spring to urge said member and hence the threading arm forwardly and through the eye of a needle resting in the needle-well and on said seat, said plunger being slidably disposed in said guiding channel, with its threading arm riding on the upper surface of said island, the upper edge of the rearwardly extending portion of said member at times bearing against the under surface of said island.

6. A needle threader as set forth in claim 5, in which said block is provided at its rear with a tapered shank suitable for holding the device between the fingers of the hand and for supporting the device in the center opening of the thread spool so that the spool may be used as a hand hold.

7. A needle threader as set forth in claim 5, and having a conical seat in the housing at the bottom of the well to rotatably support the butt end of the needle with the eye of the needle in alignment with the hooked threading arm, the angle of the conical seat being obtuse and of such degree that when any commercial size hand-sewing needle rests on said seat the eye of the needle will be in position for the pointed bill and the needle to cooperate to lead the bill through the eye of the needle, said reciprocating member having free limited vertical movement.

8. A needle threading device of the character described, comprising a casing, a needle-receiving well in said casing and a needle-eye-engaging member slidably mounted in said casing athwart said needle-receiving well, said needle-eye-engaging member being spring urged in one direction to project it through the eye of a needle mounted in said well and being provided with a finger-actuated portion for manually pushing said needle-eye-engaging member in the opposite direction, against the action of the spring, to retract it from the eye of said needle, said needle-eye-engaging member having a thread hook, said needle-eye-engaging member being integral with its said spring and with its said finger-actuated portion, said casing having a vertically disposed slot through its wall communicating with said needle well, said slot being vertically sinuous to bar a needle in the needle well from falling out through said slot.

9. A needle threader adapted to accommodate all commercial size hand-sewing needles comprising a two-part housing, a vertical needle-well in said housing, a transverse guideway in said housing, a reciprocating member closely slidably housed within said transverse guideway and comprising a sheet metal stamping having a hooked threading arm as an integral part of said member extending forwardly from the rear end of said member, said hooked arm terminating in a pointed bill, said threading arm being spaced apart from a lower portion of said member, a leaf spring bent from and extending as an integral continuation of the reciprocating member upwardly and rearwardly from said member with an actuating portion of said member extending forwardly, outwardly beyond said body

portion to be operatively engaged by a person's finger, said needle-well being adapted to receive a needle for longitudinal and axial movements only until its eye lies in the path of said hooked threading arm, a notched throat in said body to receive a thread to be engaged by said hook of the threading arm for drawing it through the eye of a needle disposed in said well, said spring being adapted to be flexed when the reciprocating member is being moved rearwardly and adapted to straighten out to pass the hook of the threading arm through the eye of said needle as the reciprocating member moves forwardly under the influence of the spring.

10. A needle threader adapted to accommodate all commercial size hand-sewing needles comprising a two-part housing, a vertical needle-well in said housing, a transverse guideway in said housing, a reciprocating member closely slidably housed within said transverse guideway and comprising a sheet metal stamping having a hooked threading arm as an integral part of said member extending forwardly from the rear end of said member, said hooked arm terminating in a pointed bill, said threading arm being spaced apart from a lower portion of said member, a leaf spring engaging said reciprocating arm, an actuating portion of said member extending forwardly, outwardly beyond said body portion to be operatively engaged by a person's finger, said needle-well being adapted to receive a needle for longitudinal and axial movements only until its eye lies in the path of said hooked threading arm, a notched throat in said body to receive a thread to be engaged by said hook of the threading arm for drawing it through the eye of a needle disposed in said well, said spring being adapted to be flexed when the reciprocating member is being moved rearwardly and adapted to straighten out to pass the hook of the threading arm through the eye of said needle as the reciprocating member moves forwardly under the influence of the spring.

11. A device as set forth in claim 1 wherein a cavity is provided in the housing for accommodating the leaf spring, said cavity being arranged so that the parting line between the two halves of the housing is off center so that the reciprocating member will ride on solid material and never on the parting line or crack between the parts.

12. A needle threader adapted to accommodate all commercial size hand-sewing needles and comprising a block having a needle-well therein opening to the top of the block, a cavity within said block, a guiding channel in said block substantially normal to said needle well and communicating with said cavity and intersecting said needle-well, an island disposed in said channel in spaced-apart relation to the top guiding surface of said guiding channel, a conical seat in said island, said seat being in axial alignment with said needle-well, a vertically disposed slot through said block communicating with said needle-well, a reciprocating member of spring metal having a finger piece on the front end thereof and having a portion extending rearwardly and then upwardly and then reentrantly forwardly, said latter portion constituting a threading arm, a hook on the upper edge of said threading arm near its free end, said hooked portion terminating in a pointed bill, the rear of said reciprocating member having an extending portion bent normal to the plane of said member and extending upwardly and rearwardly to serve as a leaf spring to urge said member and hence

the threading arm forwardly and through the eye of a needle resting in the needle-well and on said seat, said plunger being slidably disposed in said guiding channel, with its threading arm riding on the upper surface of said island, the upper edge of the rearwardly extending portion of said member at times bearing against the under surface of said island.

13. In a needle threader of the type in which a housing has formed therein a needle-well and a guideway extending transversely of said needle-well, and in which there is a horizontally reciprocating member in said guideway, said member having a hooked end threading arm, with said end terminating in a pointed bill; that improvement which comprises a conical seat formed in the housing at the base of the needle-well to guide said needle to the center of the well, the angle of divergence of the sides of the conical seat being obtuse, such that when any commercial size hand-sewing needle from No. 1 to No.

10 rests on said seat, the eye of said needle will be at the proper level to receive at least the point of the bill of the threading arm, said needle threader housing having a sinuous thread passage communicating the needle-well with the outside of the needle threader housing, parts of the confronting walls of said passage being interspersed to serve as a barrier for a needle within the well while permitting thread to pass therethrough without hindrance.

JULIAN SETH KAHN.
